UNITED STATES PATENT OFFICE.

JOHN O. McKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

WINDING-MACHINE.

1,247,980.

Specification of Letters Patent. Patented Nov. 27, 1917.

Application filed February 2, 1916. Serial No. 75,802.

To all whom it may concern:

Be it known that I, JOHN O. McKEAN, a citizen of the United States, residing at Westfield, in the county of Hampden and 5 State of Massachusetts, have invented new and useful Improvements in Winding-Machines, of which the following is a specification.

My invention is an improvement in winding machines and consists in improvements in the organization of the parts and in certain novel mechanisms for performing specific functions.

In the drawings:

15 Figure 1 is a front view in elevation of a winding machine embodying my improvements;

Fig. 1^A is a detail, in section, and on an enlarged scale of the tension mechanism, 20 shown at the bottom of Fig. 1;

Fig. 2 is an end view in elevation showing the end of the machine to the left in Fig. 1;

Fig. 3 is a detail, in plan of a portion of the tension mechanism, taken on line 3—3 of 25 Fig. 2, looking in the direction of the arrows;

Fig. 4 is an elevation of the opposite end of the machine from that shown in Fig. 2;

Fig. 5 is a sectional elevation showing a 30 part of the frame and the cam and casing and the arbor and its associated parts;

Fig. 6 is a plan view of the spindle and its bearing and the seat upon which it is secured, the dotted lines indicating the center 35 about which it is shifted to its various positions.

My improved cop winding machine, as herein shown and described, is constructed and arranged to produce a cop of the well 40 known open, self-binding wind. The thread is wound upon a quill of card-board or the like; this quill is slipped endwise onto a spindle 1 and the leading end of the thread α is fastened thereto. When the machine is 45 started the spindle and quill rotate together and the thread α , directed by the reciprocating thread guide 2, is wound onto the quill to build up the cop. The thread guide and the spindle are so connected that the thread 50 guide reciprocates rapidly along the face of the quill, laying the thread in long spirals, and provision is made to adjust the speed

relation of the two parts so that each succeeding spiral of thread, in a given direction will be laid alongside the previously laid spiral in the same direction and will bind down all spirals laid in the opposite direction. All this is old and well known, 55 constituting what is known as the "Fiji wind" and need not be elaborated.

The spindle 1 is journaled in a bearing 3 and carries a fast, slightly conical, pulley 4 and a loose pulley 5 with both of which a main driving belt 6 coöperates, said belt being driven from any suitable source of 60 power.

The thread guide eye 2 is mounted on a tang 7 rigidly connected to and carried by a tubular carriage 8 slidably mounted upon a thread guide rail 9. The rail 9 is fastened at its ends to arms 10 forming part of a housing 11 formed with hubs 12 and 13 rotatably supported by a fixed arbor 14. Within the housing 11 the arbor 14 has, loosely mounted thereon, a sleeve 15 to which is fastened a cam 16 carrying a hub gear 17, 70 said sleeve being held against endwise movement on the arbor by the hub 13 and a collar 18 that is fastened to the arbor by a screw 19. The arbor 14 is supported by an upright frame 20 made with a hollow hub 21 within which one end of said arbor is fixed so that it cannot rotate, by means of a screw 22 (Fig. 4). The cam 16 is made with a groove 75 23 into which projects a stud 24 depending from the lower side of thread guide carriage 8, said stud carrying an anti-friction roll 25.

The gear 17 is driven by a pinion 26 fast to one end of a shaft 27 which also carries a slightly conical pulley 28 connected by a belt 29 with the pulley 4, the small end of each of said pulleys being opposed to the large end of the other pulley. The belt 29 is engaged by a belt-guiding yoke 30 which is 80 slidably mounted upon a stud 31 projecting from the frame 20. This guide 30 is made with an ear formed with a tapped hole through which a screw 32 extends, said screw being rotatably mounted in a bearing 85 provided on the frame 20 and provided with a handle 33 by means of which it may be rotated to shift guide 30 on the stud 31 to exactly adjust belt 29 according to the exact speed relation desired between cam 16 and 90 95 100

spindle 1. That is, by adjusting the guide 30 along the stud 31 by means of screw 32 the speed of rotation of cam 16 with relation to the speed of rotation of spindle 1 may be increased or diminished to cause the thread guide 2 to lay the convolutions on the cop side by side, so that the cop, although formed of open spirals may be solid.

The shaft 27 is rotatably supported at one end of an arm 34 whose other end is made with two hubs 35 and 36, the former being split and clamped to the hub 21 of frame 20 by means of a screw 37 (Fig. 4). A collar 38 is arranged between the two hubs 35 and 36 and fastened to the hub 21 by a screw 22 and serves to hold arm 34 against sidewise displacement while being adjusted.

At its outer free end the arbor 14 is made with an angular vertical hole 38 within which is slidably mounted a pawl 39 consisting of a bar of metal provided for convenience with a handle 40, the lower end of the pawl 39 coöoperating with a stop 41 provided on the housing 11. The pawl 39 and stop 41 are arranged and constructed so as to permit the housing 11 to rotate freely in a direction to permit the thread guide, which is carried by the housing, to shift away from spindle 1, but to immediately check and prevent any movement of the housing 11 in the opposite direction. In other words the pawl 39 and stop 41 provide a clutch which normally prevents any rotary movement of the housing in one direction and at the same time leaves it entirely free to swing in the opposite direction.

One side of the cylindrical portion of housing 11 consists of a separable section or cover 42 fastened to the main portion by a screw 43 and on this cover 42 is secured, by means of a screw 44 an angularly adjustable counterbalance weight 45 consisting of a block of metal formed with a slot 46 through which the screw 44 extends. This weight 45 together with the weight of the cover 42 and those portions of the housing 11 at one side of the arbor 14, slightly overbalances the weight of the portions of the housing 11 and associated parts, at the opposite side of the arbor and of the parts carried thereby, with the result that the thread guide is yieldingly urged toward the spindle, but it is to be borne in mind that the clutch 39-41 normally prevents movement of the thread guide in that direction so that during the winding operation there is practically no continued pressure of the thread guide against the growing cop. This is due to the automatic "take up" action of the clutch 39-41 together with the fact that whenever the growing and rapidly rotating cop comes into contact with the thread guide the minute irregularities of the cop cause the thread guide to be kicked away from the cop slightly, whereupon it is caught and

held by the clutch 39-41 until the growing cop again touches the thread guide and the thread guide is again kicked back slightly and caught. It will thus be seen that the thread guide only engages the growing cop intermittently and each time is soon thrown out of contact therewith by the slightest irregularity in the cop. This results in more even and perfect winding and makes possible the use of very slender and light thread 75 guide parts.

The housing 11 also includes a separate casting 47 rigidly secured to the thread guide rail 9 by means of screws 48 and this casting 47 is made with a narrow slot 49 through which the thread guide tang 7 extends, said slot being of about the same width as the thickness of the tang so that the latter is guided and supported and held against vibration or chattering. The cam 85 16 rapidly reciprocates the thread guide 2 lengthwise of the spindle 1 and at each end of its stroke the direction of movement of said thread guide is abruptly reversed so that if the thread guide and its carriage included 90 any considerable mass of metal in their construction the shock of this abrupt reversal of movement would be injurious. For this reason I make the thread guide and tang from light and thin metal and the carriage 8 from a light, thin piece of tubing so that said parts acquire a correspondingly small amount of momentum during their movements. Owing to the lightness of the construction of the thread guide I find it desirable to provide a thread guide supporting rail 50 provided at its ends with legs 51 secured to the casting 47. This rail supports the thread guide eye against any pressure against the cop and pull of the thread 105 or yarn during the winding operation.

The housing 11 is made, upon its under side, with a lug 52 carrying an adjustable stop screw 53 which coöperates with the rear side of a lug 54 cast on the frame 20 to 110 limit the swinging movement of housing 11 in one direction. In order to limit the swinging movement of the housing in the opposite direction said housing is made with a lug 55 coöperating with the opposite side 115 of lug 54.

I have provided an automatic tension control in which the thread or yarn from which the cops are built is led from the supply around a rotatable spindle 56^a mounted in 120 the end of fixed spindle 56, the thread or yarn passing between two disks 57 and 58 (see Figs. 1 and 1^a), the former fast against movement on spindle 56^a and the latter, by a pin and slot connection, capable of endwise movement. From the disks, the thread passes under a drop wire 59 and upwardly over rail 50 to the thread guide eye and cop. Slidably mounted upon the spindle 56 is a sleeve 60 which is exteriorly threaded to re- 125 130

ceive upon it an adjustable nut 61 between which and disk 58 is arranged a spiral spring 62 which yieldingly presses against a loose sleeve 62^a which in turn abuts upon 5 the disk 58 and presses it against the thread or yarn as it passes around spindle 56^a and between the disks 57 and 58, the initial pressure of the spring 62 against disk 58, and therefore the initial tension on the yarn or 10 thread being determined by the adjusted position of the nut 61 on sleeve 60 and the consequent spring pressure. During the operation of building a cop, the cop, of course, grows in diameter, with the result that the 15 yarn or thread is drawn from the supply at a continually increasing rate of speed which increases the tension on the thread or yarn in exact proportion to the increase in speed and in order to counteract this and maintain 20 the proper tension, I have herein provided for automatically relaxing the tension producing device or devices as the speed of movement of the thread or yarn increases during the growth of the cop. To accomplish 25 this the sleeve 60 is made at one end with an arm 63 pivotally connected with a small sleeve 64 slidably mounted upon a cam bar 65. This cam bar 65 is pivoted at 66 to a slide 67 and its opposite end extends loosely 30 through a square sleeve 68 resting upon the top of slide 67. Sleeve 68 is pivotally connected to a square nut 69 mounted upon a screw 70 rotatably supported at its ends by slide 67 and held against endwise movement 35 thereon by a collar 71 and thumb piece 72. At its forward end the slide 67 rests upon an arm 73 forming part of the frame of the machine while the rear end of said slide is supported by the lug 55 to which it is pivotally connected by a screw 74. Thus it will 40 be clear that the slide 67 is shifted bodily on arm 73 whenever the housing is swung on arbor 14 and that the direction of this sliding movement of said slide is crosswise 45 of the axis of spindle 56. By means of the screw 70 the cam bar 65 is set in a diagonal position relatively to the spindle 56 so that it will also be clear that the bodily movement imparted to the slide 67 during the 50 growth of a cop is imparted to the cam bar 65 and the latter, acting through the sleeve 64, arm 63, sleeve 60 and nut 61, will automatically relax the pressure of the spring 62 on disk 58 thus decreasing the tension 55 effect of the two disks 57 and 58 as the winding progresses.

As is well known it is a property of a spiral spring that it increases or decreases its resistance in exact accord with the 60 amount which it is distorted from its normal spiral. This property is taken advantage of in the ordinary spring balance scales, in which the graduated plate indicating the weight is equally spaced and the 65 spring correspondingly distorted by the

weight. I take advantage of this by employing a straight cam bar which when set at the proper angle, for every inch of radial growth of a cop and consequent increased speed of the thread, will exactly compensate 70 by permitting the spring to correspondingly expand and thus decrease the tensional drag on the thread in exact proportion to the increase caused by the increase in speed. I have shown adjusting means to vary the angle of the straight cam bar, since it is not always desired to keep the tension uniform, but it may be desired to gradually increase or decrease the tension as the cop builds. 75

I have shown in the drawings and in detail in Fig. 1^A the preferred form of tension member, in which one member (57) is supported and secured upon the spindle by a yoke 57^a and has an axial perforation 57^b while the other member (58) has a hub 58^a 80 which passes through the perforation leaving an annular space. The object of this is to provide a wearing surface to protect the spindle from the cutting effect of the rapidly moving thread and a free outlet for the 85 lint, etc., which is constantly being stripped from the thread by its engagement with the tension disks. The tension device above described is not claimed in this application, but will form the subject of a divisional 90 application. 95

I have also provided a stop motion, which automatically stops the machine in case of breakage of the thread during the winding process. The drop wire 59 is pivoted at 75 100 to the arm 73 and its hub portion is formed with a cam 76 coöperating with a roll 77 provided upon one arm of a lever 78 pivoted at 79 to the frame of the machine. The other arm of lever 78 carries a pin 80 normally in engagement with a pin 81 carried by an arm 82 fast on a rock shaft 83. This rock shaft 83 has fixed to it another arm 84 that is pivotally connected with one end of a link 85 whose opposite end is pivotally 105 connected with a belt shipper 86. The belt shipper 86 which is provided with a yoke 87 straddling the belt 6 is pivoted at 88 to an arm 89 cast integral with bearing 3 and has connected to it one end of a spring 90 whose 110 opposite end is connected with said arm. The spring 90 tends constantly to shift belt shipper 86 into position to place the belt 6 on loose pulley 5 but is normally prevented from doing so by the engagement of 115 pins 80 and 81.

When the yarn or thread that is being wound onto the cop breaks the drop wire 59, being no longer supported thereby, falls, and its cam 76 acts to swing lever 78 in a 125 direction to disengage the pin 80 from the pin 81 whereupon the spring 90 shifts belt shipper 86 toward the right (Fig. 1), shifting the belt 6 onto the loose pulley 5 and stopping the machine. In order to provide 130

for manually starting the machine and resetting the "break" stop motion mechanism, the rock shaft 83 is provided with a handle 91.

5 Herein I have also provided means for automatically stopping the machine when the cop that is being made reaches a predetermined size. This means comprises a screw 92 rotatably mounted on slide 67 and 10 held against endwise movement thereon by collars 93 and 94 and provided with a nut 95 adjustably mounted on said screw. By rotating the nut 95 it may be set so that when the cop reaches the desired size said 15 nut engages the lever 78 and thereby disengages the pins 80 and 81 so as to stop the machine.

Cops of the kind that my improved machine is designed to make are produced 20 either cylindrical or conical in form and herein I have provided for producing cops of either form. To this end the frame 20 is made with a seat 96 upon its upper surface for the bearing 3, said seat being made 25 with a series of tapped screw holes 97 and 98, and the bearing 3 is made with ears 99 which are fastened to the seat 96 by screws 100 engaging the proper screw holes. When the bearing 3 is fastened in place on the 30 seat 96 by inserting the screws in the holes 97 as shown in the drawings, the axis of the spindle 1 is parallel with the path of movement of thread guide 2 and a cylindrical cop will be produced. When it is de- 35 sired to produce a conical cop the screws 100 are removed from holes 97 and transferred to one or the other of the three sets of holes 98 according to the degree of conicity de- 40 sired, it being clear that the holes 98 are positioned so that when used to fasten bearing 3 to seat 96 the axis of the spindle 1 will be oblique with relation to the path 45 of movement of the thread guide. Several sets of holes 98 are provided so that cops of either of several different conical shapes may be produced by using a suitable quill.

In connection with this provision for adjustment of bearing 3 on seat 96 a feature of my invention resides in the peculiar connection, above described, between lever 84 and shipper 86 which permits of lateral adjustment of said shipper relatively to arm 84 without requiring adjustment of said connection, herein shown as the link 85. It 50 will be observed (see Fig. 6) that in its various adjustments the spindle is shifted about a center α and the link 85 is connected to arm 84 and shifter 86 so as to be capable of free movement. The connection between 55 link 85 and arm 84 is positioned approximately between the extreme positions which the spindle bearing may assume. The result is that adjustment of the spindle bearing produces no perceptible result upon the 60 shifter and the belt shifter functions prop-

erly without any necessity for adjustment or attention in whatever position the spindle bearing may be.

The operation is as follows: The thread to be wound having been threaded through 70 the tension disks, 57, 58, under the drop wire 59 and over the guide-support 50 to the thread guide eye and secured to the quill, the machine is started by lifting the handle 91, thus, through arm 84 and link 85, shifting the belt shipper 87 to shift the driving belt from the loose pulley 5 to the outer edge of the cone pulley 4. This movement is against the effort of spring 90 which constantly tends to shift the driving belt to 80 the loose pulley. The lifting of handle 91 also moves arm 82 and causes the engagement of pins 80, 81 (Fig. 1). This engagement serves to hold the driving belt in operative position against the effort of 85 spring 90 so long as the engagement is maintained. The engagement is broken, however, whenever the drop wire falls by reason of a broken thread, the falling of the drop wire lifting the arm 78, through cam 76 and 90 roll 77 thus disengaging the pins 80, 81 and permitting the spring 90 to draw the shipper and shift the driving belt onto the loose pulley 5. This shifting is also automatically accomplished when the cop attains the 95 predetermined size by means of an adjustable nut 95, mounted upon a slide or carriage 67. The growth of the cop gradually shifts the housing 11 and draws the carriage inward until the nut 95 engages arm 100 78 and lifts it, thus disengaging the pins 80, 81, and permitting spring 90 to operate the shift and thus stop the machine. Slight irregularities in the cop or the most recently laid coils, as the cop rotates, continually 105 strike the thread guide and force it backward. If this effect were continuous and uncontrolled the result would be that the thread guide and its supports would be continuously vibrated and the thread guide 110 would necessarily require to be strongly built to withstand such usage, while the continual strike and repulse action would be damaging to the cop. This is prevented by the pawl 39 co-operating with a stop 41. 115 The pawl 39 is shown as operating by gravity and, as the stop 41 is shifted by the cop, through the thread guide 2 carried by the housing 11 to which the stop 41 is secured, the pawl instantly drops and continually 120 maintains its engagement with the stop and securely locks the parts against any return swing. The positioning of the spindle 1 and its bearing 3 for cylindrical or conical cops does not disturb in any way the connection 125 by which the break-and-size-stop motions are made effective to shift the driving belt, the connection being universally jointed and so positioned in the machine with reference to the point about which the spindle is 130

moved to its various positions, that practically no derangement of the parts occurs and no adjustment is necessary.

I claim:—

- 5 In a winding machine, an arbor supporting a cam and a swinging thread guide; that cam and thread guide; a cap-carrying spindle; an engaging member supported by the arbor; a stop connected to the swinging 10 thread guide and moving in unison there-

with, all organized to cause the engaging member to follow up the movement of the stop in one direction and prevent movement in the other direction.

Signed by me at Boston, Massachusetts, 15 this 18th day of January, 1916.

JOHN O. McKEAN.
